MORTON O. SNEDIKER, OF CHICAGO, ILLINOIS, ASSIGNOR TO THE POWERS REGULATOR COMPANY, OF CHICAGO, ILLINOIS, A CORPORATION OF ILLINOIS

ELECTROHYGROSTAT

Application filed June 10, 1931. Serial No. 543,379.

My invention relates to devices for controlling the moisture content of air and particularly to a device of this character in which electrical power is used for actuating 5 the moisture admission apparatus.

I am aware that electro-hygrostats have been suggested and several thereof operate satisfactorily where low voltage current is utilized or where a low voltage relay circuit 10 is employed. The latter design is objectionable because of the additional cost of apparatus, including transformers, etc.

An object of my invention is to provide an electro-hygrostat in which high voltage current is exclusively used. In order to avoid destructive arcing at the contacts special 15 novel apparatus is utilized, and continued satisfactory operation over long periods is assured. To accomplish the desired result I 20 utilize the principle of supplementing the contact effected by the moisture-sensitive element by motion transmitted to the contacts by the action of the magnet utilized to close the primary circuit. This in itself is 25 not new, but variations and improvements are made which render such devices less troublesome. For example, a common fault is that arising from an abnormally closed circuit due to adherence of the secondary 30 contacts by fusing. In my apparatus the arrangement is such that the powerful expansive force of the moisture-sensitive element is available to separate the contacts in case of incipient fusion. This implies relatively great rigidity of the fixed contact 35 piece and consequently the requirement for relatively great force in order to flex said contact piece to assist in the making of the original contact. This is secured by proper 40 arrangement of the parts that will now be described.

My invention will be more readily understood by reference to the accompanying drawings in which:

45 Fig. 1 is a side elevation of an electro-hygrostat constructed in accordance with my invention;

50 Fig. 2 is a similar view showing the parts in another position, and

Fig. 3 is a plan view.

In the drawings the device of my invention is shown as mounted on a hollow base 10 and includes a moisture-sensitive element 11 abutting at one end against an adjusting screw 12 and at the other end against the 55 short arm 13 of a bell crank fulcrumed at 14. The other arm 15 of the bell crank carries a contact piece 16. The complementary contact piece 17 is mounted on a relatively rigid arm 18 of insulating material fixed to 60 a support 19. An insulating material, such as fibre, is selected having considerable rigidity but still sufficiently flexible to enable its being bent the small amount necessary. Wires extending from the contacts 16, 17 65 constituting the secondary circuit, extend to a magnet 20, the projecting core of which serves to actuate an armature 21. The armature is mounted for oscillation on a fulcrum piece 22, the projecting outer end 23 of the 70 armature being curved or angular as shown, and serving to support a supplementary operating member for the secondary contacts. This member comprises an arm 24 connected through a pin 25 and spring 26 to the portion 23 of the armature and at its outer end 75 carrying the foot 27 that underlies the contact piece 18.

The armature also carries an arm 28 having a circuit closer 29 thereon for closing the 80 primary circuit indicated by the contacts 30, this arm being resiliently connected through the spring 31.

In Fig. 2 the parts are shown in idle or 85 inactive position in which case the flat surfaces of the member 24 and the projection 23 are in contact and the armature is permitted to be drawn toward the core to an extent sufficient to close the primary circuit 90 30 with very little force. However, as the arm approaches the point of contact with the core, the foot 27 has been elevated in contact with the contact piece 18 and much greater force is necessary and available in 95 order to slightly bend said contact piece 18. At that point the parts 23 and 24 change their position, the part 24 rocking on the curved portion at the end of the straight part of the armature projection thus exerting an augmented force or leverage and 100

exerting the full force of the magnet through a shortened lever. Thus when the moisture-sensitive element retracts due to the lowering of the moisture content of the air, the spring 11a moves the bell crank toward the position where the slightest contact between the contacts 16, 17 results in energizing the magnet and closing the primary circuit. To prevent fluttering, the movement of the armature to fully closed position results in bending the contact piece 18 sufficiently to make a good contact.

When the air contains too great a percentage of moisture the expansion of the moisture-sensitive element results in a thrust on the bell crank. This thrust being of relatively great force, and as the contact piece 18 is relatively rigid, any partial fusing of the contacts 16, 17 will be broken and immediately upon breaking the circuit through the magnet, the pressure will be released beneath the contact piece and the circuit will be completely broken without an arc.

Thus I am able to utilize high voltage current without excessive arcing by reason of the proper arrangement of the parts. This result may be accomplished in manners other than herein shown, and I do not wish to be limited except as indicated in the appended claims.

I claim:

1. In combination, a support, a moisture-sensitive element thereon, an arm movable by said element, said arm carrying an electrical contact, a relatively rigid but slightly resilient arm fixed to the base and carrying a complementary contact, a magnet and armature, a second pair of contacts adapted to be closed by said armature, said armature being pivotally mounted, an arm connected at one end to the armature and at the other end underlying said resilient arm, the connection between the armature and arm being resilient.

2. In combination, a support, a moisture-sensitive element thereon, an arm movable by said element said arm carrying an electrical contact, a relatively rigid but slightly resilient arm fixed to the base and carrying a complementary contact, a magnet and armature, a second pair of contacts adapted to be closed by said armature, said armature being pivotally mounted, an arm connected at one end to the armature and at the other end underlying said resilient arm, the connection between the armature and arm being resilient, and movable at different points in the armature stroke.

3. In a hygrostat, the combination of a moisture-sensitive element, a bell crank, one arm of which is contacted by said element and the other arm carries one of a pair of high voltage contacts in a circuit, a relatively rigid bendable arm carrying the second of the pair of contacts, a magnet in said cir-

cuit, a pivoted armature, a second circuit closer carried by the armature, a contact-assisting arm resiliently connected to and adapted to be moved by the armature and having a portion engaging the bendable contact arm, and means in said resilient connection for changing the leverage exerted by the armature on said contact-assisting arm.

4. In a hygrostat, the combination of a moisture-sensitive element, a bell crank, one arm of which is contacted by said element and the other arm carries one of a pair of high voltage contacts in a circuit, a relatively rigid bendable arm carrying the second of the pair of contacts, a magnet in said circuit, a pivoted armature, a second circuit closer carried by the armature, a contact-assisting arm resiliently connected to and adapted to be moved by the armature and having a portion engaging the bendable contact arm, a means in said resilient connection for progressively increasing the force exerted by the armature on said contact assisting arm.

5. In a hygrostat, the combination of a moisture-sensitive element, a bell crank, one arm of which is contacted by said element and the other arm carries one of a pair of high voltage contacts in a circuit, a relatively rigid bendable arm carrying the second of the pair of contacts, a magnet in said circuit, an armature in the general form of a bell crank having the portion at one side of its fulcrum overlying the core of the magnet and the portion on the other side of the fulcrum providing an operating member, a contact-assisting arm for engaging said contacts, said arm having a flat surface, spring held against a flat surface on said member, whereby the energized position of the armature results in a spring resisted rocking movement in the connection between the arm and the armature and a change in the leverage exerted by the arm.

In testimony whereof I have affixed my signature.

MORTON O. SNEDIKER.
